EXPANDING FOOT PIECE FOR WHIPSTOCKS

James D. Hughes, Dallas, Tex., assignor of one-half to Eastman Oil Well Survey Corporation of California and one-half to Eastman Oil Well Survey Company of Delaware

Application October 28, 1937, Serial No. 171,465

1 Claim. (Cl. 255—1)

The invention relates to a whipstock of the type which may be lowered into the well bore anchored in position to cause deflection of the drill bit and thereafter the anchoring portion thereof released and the whipstock removed from the well bore 5 along with the drill bit.

In directional drilling it is desirable to set the whipstock in the well bore in a predetermined and oriented position so as to direct the well bore in the desired manner. The practice has therefore grown up of inserting the drill bit and the whipstock into the well bore as a unit and orienting the whipstock so that the deflecting face will direct the drill bit in the desired manner. It is 10 of course necessary to anchor the whipstock so that when the drill bit is released therefrom to perform the drilling operation that the whipstock may be securely anchored in position.

The present invention contemplates an expanding foot piece or anchor for the whipstock 20 which can be set to hold the whipstock in the desired predetermined position and which may thereafter be released so that the whipstock may be readily removed.

Another object of the invention is to provide 25 a wedge type anchor for removable whipstocks.

Still another object of the invention is to provide a telescoping foot piece for whipstocks so that it may be wedged in position in the well 30 bore to anchor the whipstock.

Still another object of the invention is to offset a whipstock in a well bore by moving the base thereof laterally in the direction in which the well bore is to be deflected.

Other and further objects of the invention will 35 be readily apparent when the following description is considered in connection with the accompanying drawing wherein:

Fig. 1 is a vertical sectional view of the whipstock assembled and ready for connection to the 40 drill bit.

Fig. 2 is a side elevation of the whipstock lowered into position and set in the well bore with the drill bit in position to be released therefrom.

Figs. 3 and 4 are sections taken on the lines 3—3 and 4—4 of Fig. 1, respectively.

Fig. 5 is a bottom plan view of the whipstock showing the arrangement of the teeth thereon 50 to hold the whipstock in position.

The upper end of the whipstock is of the general type shown in the patent to McVicar, 1,970,761, granted August 21, 1934, and includes a collar 2 which has a passage 3 therethrough to receive the drill stem 4. The drill stem has a

drill bit 5 connected thereto. A pin 7 is arranged to pass through the opening 8 in the collar 2 and in this manner the whipstock is fastened to the drill stem so that the assembly may be lowered into the well bore. This pin prevents relative rotation of the whipstock with respect to the drill stem so that if it is desired to orient the drill stem into position the operator is assured that the whipstock will be fixed in the desired and predetermined direction when his orientation has been completed. Of course, the pin 7 is arranged to shear when a sufficient weight is placed upon the drill stem so that the drill bit may advance to cut away the side 10 of the well bore 11.

The whipstock 12 includes the body portion 13 which has the inclined deflecting face 14 thereon. This body 12 may be of any desired length or configuration and the angle of the deflecting face 14 may be varied for different whipstocks, depending upon the angle of deflection which is desired.

In order that the whipstock may be readily anchored in position when it reaches the desired elevation a foot piece 20 has been connected thereto. This foot piece has a toothed lower end 21 so that it may bite into the bottom 22 of the well bore 11 and is of a diameter to fit into the well bore. This piece has a wedged or tapered face 23 thereon which is inclined with respect to the longitudinal axis of the whipstock and the foot piece. This face 23 may have a dove-tail groove 25 therein which is arranged to fit with a dove-tail tongue 26 which is provided on the lower tapered end 27 of the whipstock body 13. In this manner there may be relative sliding movement between the foot piece and the whipstock, and as seen in Fig. 2, when the foot piece is anchored against the well bore, pressure applied to the whipstock body 13 will cause it to slide along the face 23 to assume the expanded position there shown, in that the whipstock will be moved to the left so that the heel 30 thereof will wedge against the side of the well bore and at the same time the foot piece 20 will be wedged against the opposite side 31 of the well bore.

This sliding movement will also move the base of the whipstock to the left so that the deflecting face 14 assumes a greater inclination than its normal angle of inclination with respect to its longitudinal axis of the well bore. In this manner the angle of deflection may be increased somewhat.

A retainer pin 40 is carried by the foot piece 20 and as seen in Fig. 1 it projects into the dove-

tail groove 25. The tongue 26 on the lower end of the whipstock is cut away to provide a space 33 which terminates in the upper shoulder 34 and the lower shoulder 35. In this manner the relative sliding movement of the foot piece and the whipstock is limited. In the upper position the whipstock may be lowered into the well bore and in the lowermost position as shown in Fig. 2 the foot piece limits the downward movement of the 10 whipstock.

After the whipstock has served its purpose and the well bore has been deflected the drill stem 4 will be raised to draw the drill bit 5 up against the collar 2. Further raising of the drill stem 15 lifts the whipstock 13 so as to withdraw the heel 30 from engagement with the well bore and to allow the foot piece to telescope along the bottom 27 of the whipstock to its retracted position. In this manner the whipstock is readily removable. 20 Any desired means may be provided to prevent inadvertent telescoping of the foot piece until a predetermined pressure is exerted thereon.

Broadly, the invention contemplates a removable type of whipstock which can be lowered into the well bore and anchored into position and readily withdrawn by merely lifting up on the whipstock.

What is claimed is:

A retrievable whipstock including a body, means at the top thereof to receive the drill stem and drill bit for lowering and retrieving the whipstock, a deflecting face on said body, a tapered 10 bottom on said body inclined across from the back, a dovetailed tongue projecting from said bottom, a cutaway portion between the ends of said tongue to provide spaced stop shoulders, a foot piece, a top face thereon which is complementary to said bottom, a dovetail groove to receive said tongue to slide therein, and a stop pin 15 projecting into said groove to be abutted by said shoulders to limit the movement of the body relative to said foot piece and to suspend the foot 20 piece on the body during lowering and retrieving.

JAMES D. HUGHES.
